Patented Feb. 2, 1915.

Fig. 1 -

UNITED STATES PATENT OFFICE.

DALEWOOD M. CLARK, OF NEWBURY WOODSWAY, NEW YORK, ASSIGNEE TO CHOUSE-HINDS COMPANY, OF SYRACUSE, NEW YORK, A CORPORATION OF NEW YORK.

INVENTIONAL APPEARANCE.

1,126,848.

Specification of Letters Patent.

Patented Feb. 2, 1915.

Original application filed February 12, 1911, Serial No. 800,618. Renewed October 20, 1911, Serial No. 857,452. Divided and this application filed July 2, 1912, Serial No. 407,125.

To all whom it may concern:

Be it known that E. Raymond M. Clark, of North Tonawanda, in the county of Erie and State of New York, has invented a new and useful Electrical Appliance, of which the following is a specification:

This invention has for its objective the production of an electrical appliance and supporting means therefore particularly applicable for use in panel boards, and it consists in the combinations and constructions hereinafter set forth and claimed.

In describing this invention reference is had to the accompanying drawing in which like characters designate corresponding parts in all the views.

Figure 1 is a plan view of the base and associated parts of my electrical appliance or switch, the same being shown as part of a panel board. Fig. 2 is an end elevation of the base of the switch and contiguous ends of the conducting bus of the panel board, the cap and the base of the panel board being shown in section. Fig. 3 is a cross sectional view of the base of this appliance, the rotary switch member being removed and contiguous parts of the panel board being also shown. Figs. 4 and 5 are plan and inverted plan views of the base. Fig. 6 is an inverted plan of the cap.

1 is the base having a central recess 2 and a set of recesses 3 on diametrically opposite sides of the recess 2 and opening through the side walls of the base thereby forming projections 4 on diametrically opposite sides of the recess 2.

As here shown the base is substantially rectangular in form and the central recess 2 is shown as circular, and the sets of recesses 3 are located at diagonally opposite corners of the rectangular base 1 and open through the top and side faces thereof. The projections 4 are located on the remaining two diagonally opposite corners of the base.

5 are a pair of terminals located in the recesses 3 and secured to the bottoms of the recesses by screws 6 extending through holes 7 into the base from the under or rear side thereof, the screws 6 threading into the terminals 5.

8 is a second set of terminals mounted on the top faces of the projections 4 and secured thereto by screws 9 extending through holes 10 opening through the side of the base

side of the base 1, portions of the terminals 5 and 8 extending into the central recess 2 into the path of the switch arms to be described.

The base 1 is secured to the base 11 of the panel board by means of screws 12 and 13 extending through plates 14 and 15 associated respectively with the terminals 5 and 8, from the upper side of the base, the screws 12 and 13 extending through passages 16 and 17 in the base 1 and threading at their lower ends into conducting bus bars 18 and 19 on the panel board, there being one pair of bus bars 18 connected to the pair of screws 12, and a similar pair of bus bars 19 connected to the pair of screws 13.

As seen in Fig. 5, the base 1 is formed on its under or rear side with recesses 20 and 21 at its corners for receiving the offset or raised ends 22 and 23 of the bus bars 18 and 19. Thus by the formation of the recesses 20, 21, the opposing ends of the bus bars 18 and 19 are separated by ribs 24 and the bus bars 18 and 19 of each pair are separated by the intervening portions 25 of the base 1. Said offset or raised ends 22 and 23 form offset surfaces on the base 1 of the panel board which engage the lower face of said base 1 and support the same above the upper face of the base 11 and also engage sides of the recesses 20 and 21 and hold the base 1 from turning movement.

26 is the shank of the rotary switch member having two pairs of arms or knives 27, 28 located within the central recess 2 in position to coact respectively with the terminals 5 and 8, the shank having a button or hand engaging piece 29 screw threaded on its outer end.

30 is a cap of insulation rectangular in general outline and fitting over the base 1 and having the side walls thereof skirting the side walls of the base 1 and closing the outer ends of the recesses 3, the cap 30 entirely inclosing the base 1, and the lower edge thereof preferably being extended beneath the bottom face of the base and arranged to rest upon the base 11 of the panel board. As here shown the side walls of the cap 30 are formed with notches 31 through which the bus bars 18 and 19 extend side edges of 105 and bars engaging with sides of the notches to prevent the cap 30 from turning.

The shank 26 of the switch member en-

tends through the top of the cap and the button 29 serves to hold the cap from removal.

Owing to the construction of the base 1, 5 and the cap 30 and the arrangement of the terminals 5 and 8 and the switch arms, the terminals and switch arms are readily accessible upon the removal of the cap.

This application is a division of my pending application Sr. No. 657,621, Oct. 30, 10 1911, renewal of application Ser. No. 609,519, filed February 18, 1911.

What I claim is:

1. An electrical appliance comprising a 15 base of insulation substantially rectangular in general plan and formed with a central recess and with a set of recesses opening into the central recess on diametrically opposite sides of the recess, the set of recesses being 20 located at diagonally opposite corners of the base and opening through the side faces thereof thereby forming projections located at the two remaining diagonally opposite corners, a pair of terminals mounted on the 25 bottoms of the set of recesses, a pair of terminals mounted on the top faces of said projections, a rotary switch member located in the central recess and coacting with said terminals, and a cap of insulation rectangular 30 in plan fitting over the base and having the side walls thereof skirting the side walls of the base and closing the outer ends of the set of recesses, substantially as and for the purpose set forth.
- 35 2. In combination, a base of insulation formed with a central recess and with a set of recesses opening into the central recess on opposite sides thereof and also through side faces of the base, thereby forming projections located on substantially diametrically opposite sides of the central recess, a pair of terminals located on the bottoms of the set of recesses, a pair of terminals mounted on said projections, a cap of insulation 40 fitting over the base and having the side walls thereof skirting the side walls of said base and closing the outer ends of the set of recesses, a rotary switch member located on substantially diametrically opposite sides of the central recess, a pair of terminals located on the bottoms of the set of recesses, a pair of terminals mounted on said projections, a cap of insulation 45 fitting over the base and having the side walls thereof skirting the side walls of said base and closing the outer ends of the set of recesses, a rotary switch member located in the central recess and coacting with said terminals, the switch member having a stem extending through the cap of insulation and provided with engaging means on the outside of said cap, and supporting means for engaging the lower face of the base and sides of said first- 50 mentioned recesses and for engaging the lower edges of the side walls of the cap and sides of said notches, substantially as and for the purpose specified.
- 55 3. In combination, a base of insulation formed with a central recess and with a set of recesses opening into the central recess on opposite sides thereof and also through side faces of the base, thereby forming projections located on substantially diametrically opposite sides of the central recess, a pair of terminals located on the bottoms of the set of recesses, a pair of terminals mounted on said projections, a cap of insulation fitting over the base and having the side walls thereof skirting the side walls of said base and closing the outer ends of the set of recesses, said side walls being 60 extended beneath the bottom face of the base and having their lower edges formed with notches, a rotary switch member located in the central recess and coacting with said terminals, the switch member having a stem 65

the set of recesses, a pair of terminals mounted on said projections, a cap of insulation fitting over the base and having the side walls thereof skirting the side walls of said base and closing the outer ends of the set of recesses, said side walls being extended beneath the bottom face of the base, a rotary switch-member located in the central recess and coacting with said terminals, the switch-member having a stem extending through the cap of insulation and provided with engaging means on the outside of said cap, and supporting means having a surface for coacting with the lower face of the base, and a second surface depressed below the first-mentioned surface for coacting with the lower edges of the side walls of the cap, substantially as and for the purpose specified.

4. In combination, a base of insulation having its lower face formed with recesses, 85 said base being formed with a central recess and with a set of recesses opening into the central recess on opposite sides thereof and also through side faces of the base, thereby forming projections located on substantially diametrically opposite sides of the central recess, a pair of terminals located on the bottoms of the set of recesses, a pair of terminals mounted on said projections, a cap of insulation fitting over the base and having the side walls thereof skirting the side walls of said base and closing the outer ends of the set of recesses, said side walls having their lower edges formed with notches, a rotary switch member located in the central 90 recess and coacting with said terminals, the switch member having a stem extending through the cap of insulation and provided with engaging means on the outside of said cap, and supporting means for engaging the lower face of the base and sides of said first-mentioned recesses and for engaging the lower edges of the side walls of the cap and sides of said notches, substantially as and for the purpose specified.

5. In combination, a base of insulation having its lower face formed with recesses, 100 said base being formed with a central recess and with a set of recesses opening into the central recess on opposite sides thereof and also through side faces of the base, thereby forming projections located on substantially diametrically opposite sides of the central recess, a pair of terminals located on the bottoms of the set of recesses, a pair of terminals mounted on said projections, a cap of insulation fitting over the base and having the side walls thereof skirting the side walls of said base and closing the outer ends of the set of recesses, said side walls being 105 extended beneath the bottom face of the base and having their lower edges formed with notches, a rotary switch member located in the central recess and coacting with said terminals, the switch member having a stem 110

extending through the cap of insulation and provided with engaging means on the outside of said cap, and supporting means having surfaces for engaging the lower face of 5 the base and sides of said first-mentioned recesses and having surfaces depressed beneath the first-mentioned surfaces for engaging the lower edges of the side walls of the cap and sides of said notches, substantially as and for the purpose set forth. 10

In testimony whereof, I have hereunto signed my name in the presence of two attesting witnesses, at North Tonawanda, in the county of Erie, in the State of New York, this 10th day of June, 1912.
